DESIGN FOR A HANDKERCHIEF DISPLAY UNIT

Sylvia Loeb, New York, N. Y.

Application March 29, 1939, Serial No. 83,898

Term of patent 3½ years

To all whom it may concern:

Be it known that I, Sylvia Loeb, a citizen of the United States of America, residing in New York city, in the Borough of Manhattan, county and State of New York, have invented a new, original, and ornamental Design for a Handkerchief Display Unit, of which the following is a specification, reference being had to the accompanying drawing, forming part thereof, wherein

Figure 1 is a front elevational view of a handkerchief display unit showing my new design.

Figure 2 is a top plan view of the handkerchief display unit shown in Figure 1.

The rear of the handkerchief display unit is substantially the same as the front.

The circular elements in each fold of the handkerchief display unit, as shown in Figure 2, represent paper, which is an integral part of the design.

I claim:

The ornamental design for a handkerchief display unit, substantially as shown and described.

SYLVIA LOEB.
